UNITED STATES PATENT OFFICE.

WILLIAM J. PERONTO, OF HARDWOOD, MICHIGAN.

LOG-LOADER.

1,224,565.

Specification of Letters Patent.

Patented May 1, 1917.

Application filed September 8, 1916. Serial No. 119,061.

To all whom it may concern:

Be it known that I, WILLIAM J. PERONTO, a citizen of the United States, residing at Hardwood, in the county of Dickinson and 5 State of Michigan, have invented certain new and useful Improvements in Log-Loaders; and I do hereby declare the following to be a full, clear, and exact description of the invention, such as will enable 10 others skilled in the art to which it appertains to make and use the same.

This invention relates to new and useful improvements in a log loader and one of its 15 objects is the provision of a device of this character, which shall be simple, durable and efficient, and which may be manufactured and sold at a comparatively low cost.

Another object of this invention is to provide a base having rotatably secured thereon 20 a mast to which is attached a block and tackle for loading logs on a sleigh or car.

A further object of this invention is to provide means whereby the mast may lean 25 to a point over the center of the car or sleigh, so that when logs are raised by the block and tackle they will be swung directly over the car or sleigh, obviating the necessity of swinging the logs laterally after they have been raised to properly position them 30 over the car or sleigh.

A still further object of this invention is the provision of means whereby the device is capable of loading logs upon a car or 35 sleigh from either side thereof without changing the position or turning the device around.

With these and other objects in view as will become more apparent as the description proceeds, the invention consists in certain 40 novel features of construction, combination and arrangement of parts as will be hereinafter more fully described and claimed.

For a complete understanding of my invention, reference is to be had to the following description and accompanying drawings, in which:—

Figure 1 is a front elevation of a log loader, constructed in accordance with my 50 invention,

Fig. 2 is a side elevation of the same,

Fig. 3 is an enlarged fragmentary trans-

verse sectional view illustrating the means of securing the mast to the base.

Fig. 4 is a detail elevation of the means of 55 connecting the block and tackle to a log,

Fig. 5 is a plan view of the means for connecting guy cables and the block and tackle to the top of the mast, and

Fig. 6 is a fragmentary elevation of the 60 mast illustrating the means of swivelly connecting the block and tackle to the upper end of the mast.

Referring in detail to the drawings, the numeral 1 indicates as an entirety a base in 65 the formation of a sleigh, consisting of a pair of parallel extending runners 2 and connected together by transverse beams 3 which are recessed intermediate their ends and have secured thereto bearings 4 for rotatably receiving a mast supporting member 5. A mast 6 is secured centrally to the mast supporting member 5 in any suitable manner and has swivelly connected to its upper end a plate 7. The plate 7 has connected to 70 one end thereof a pair of guy cables 8 which are adapted to be fastened to stumps or anchors 9 located to one side of the base 1. The mast 6 has secured adjacent its upper end a ring 10 to which a pair of guy cables 80 11 are secured. The guy cables 11 are in turn connected to each end of the mast supporting member 5 by means of eye-bolts 12 for bracing the upper end of the mast. A ring 13 is secured to the mast at a point 85 adjacent the lower end thereof, and has secured thereto a pair of guy cables 14 which are in turn tied or otherwise secured to eye-bolts 15 carried by the runners 2, whereby one or the other of the cables 14 may be 90 slackened to allow the mast 6 to lean to one side of the base 1 when desired.

A block 16 is pivotally connected to the plate 7 and has connected thereto a cable 17 which passes through a block 18. After the 95 cable passes through the block 18 it is passed through the block 16 and through a block 19 which is detachably secured to the mast 6 and mast supporting member 5 by means of hooks 20 and eye-bolts 21. Draft animals or 100 other draft power may be connected to the free end of the cable 17. A pair of links 22 are connected to the block 18 by means of a ring 23 and have secured to the ends thereof

hooks 24 for an engagement with each end of a log. Suitable ropes or cables 25 are connected to each of the hooks for returning the hooks to a lower position after a log has been raised.

The mast 6 has secured thereto a plurality of steps 26 whereby a person or persons may climb up the mast to adjust the block and tackle thereto when desired.

10 In operation, a sleigh or car is positioned to one side of the base 1 and the mast 6 is allowed to swing to one side of the base and overlie the car or sleigh to be loaded by slackening one of the cables 14. The log 15 to be loaded upon the car or sleigh is then attached at each end thereof to the hooks 24 and by pulling upon the free end of the cable 17 by the draft power, the log is raised upwardly and deposited within the car or 20 sleigh. The hooks are then released from the log and are pulled downwardly by the ropes 25 to again be attached to another log. When it is desired to load a car or sleigh upon the other side of the base, the 25 plate 7 is rotated upon the mast and the guy cables 8 are attached to anchors located upon the opposite side of the base. When the plate 7 is rotated, the block and tackle is then positioned upon the reverse side or 30 opposite side of the mast. The block 19 is then detached from the mast and positioned upon the opposite side which is also pro-

vided with eye-bolts to receive the hooks 20. The device is then in a position ready to load logs from the opposite sides by releasing the opposite cable 14 so that the mast 6 may lean over the car or sleigh to be loaded. 35

While I have shown and described the preferred embodiment of my invention, it will be understood that minor changes in 40 construction, combination and arrangement of parts may be made without departing from the spirit and scope of the invention as claimed.

Having thus described my invention, what 45 I claim is:—

A log loader comprising a base, a mast rotatably secured to said base, a plate swiveled to the upper end of the mast, means for supporting the upper end of the mast, a 50 ring secured to the mast adjacent its lower end, guy cables secured to the ring and detachably secured to the base whereby the mast may be inclined to either side of the base, and a block and tackle pivotally connected to the base and detachably secured to the mast at the lower end thereof for elevating logs. 55

In testimony whereof I affix my signature is presence of two witnesses.

WILLIAM J. PERONTO.
